RELAY FOR RELIABLE OPERATION WITH
DEFINITE EXCITATION

Henri Perret, Zug, Switzerland, assignor to Landis & Gyr, A. G., a body corporate of Switzerland

Application January 4, 1944, Serial No. 516,994
In Switzerland December 21, 1942

Section 1, Public Law 690, August 8, 1946
Patent expires December 21, 1962

6 Claims. (Cl. 175—336)

1

The present invention relates to relays and more particularly to relays which are to be actuated with a definite or given excitation.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, and improvements herein shown and described.

The accompanying drawings, referred to herein and constituting a part hereof, illustrate one embodiment of the invention, and together with the description, serve to explain the principles of the invention.

Relays are of very common application in electrical engineering and consist principally of an electromagnet and an armature. The latter is usually under action of a spring and may be designed as a hinged, rotary or plunger armature. But no matter what type is employed two main groups can be distinguished for all relays according to their application. In the first group the relay has to perform a certain work at a specified time, which can be readily accomplished by adequate excitation of the magnet. In the second group the relay has to do its work with a definite excitation and even with marginal excitation the movement should be sure and distinct.

The present invention refers to relays of the second group. With such relays the magnetic force of attraction takes a hyperbolic course in function of the armature distance while the resetting force of the counter-spring is linear. To obtain precise effects the resetting spring must be loaded. When the excitation of such a relay is brought about, the armature begins to move as soon as the magnetic force of attraction is greater than the load by the resetting spring. As the space between the curve of the magnetic force of attraction and that of the resetting power of the counter-spring—both powers being shown in function of the armature stroke—represents a measure of the working power of the armature, it is easy to see that this capacity for work remains feeble, seeing that both curves take a similar upward trend. Apart from this feeble capacity for work it has been found to be particularly disadvantageous for certain application purposes, e. g. with self-acting branch switches, that with such relays no sure response for a

2

definite predetermined excitation can be obtained.

The object of the present invention is to create a relay whose armature possesses a greater capacity for work and an increased reliability in timed operations.

This can be accomplished by placing a lead cam arrangement under action of a spring and so fitting it to the relay armature that the latter is retained in its rest position and released only upon the electromagnetic force of attraction in association with quite a definite relay excitation.

In the accompanying drawing there are shown for purposes of illustration only, certain preferred embodiments of the present invention together with a few diagrams. In the drawing:

Fig. 1 is an example of embodiment as plunger armature relay;

Figs. 2, 3, 4 and 5 are diagrams;
Fig. 6 illustrates a form of an armature and
Fig. 7 an example of embodiment as rotary armature relay.

Fig. 8 shows an example of embodiment as hinged armature relay;

Fig. 9 a lateral view thereof;
Fig. 10 illustrates a further example of embodiment of the relay armature and
Fig. 11 a lateral view thereto.

Referring more particularly to Fig. 1, the invention is illustrated as comprising a rotation-symmetrical relay armature designated 1, being provided at its lowest part with a bulge and bearing a little further up an arresting ring 2. The double-flanged coil holder 3 carries the exciting winding 4 and is equipped on its lower flange with two lugs or bearing noses 5 in each of whose centers 6 a toggle lever 7 is hinged and movable to a slight extent. The rollers 8 are borne slightly rotary on one shank of the toggle levers 7. The other two shanks of the toggle levers 7 are turned inwardly towards each other with their ends linked together by an axis 12. A regulating spring 13 fulcrumed at point 14 bears from below against the axis 12 and can be so adjusted by means of a set screw 15 that the rollers 8 are urged against the relay armature 1 in the direction of the arrows 9.

The resetting spring 10 is supported by the rim 11 projecting from the upper flange into the interior of the coil holder 3 and tends to press the relay armature 1 downwardly.

The action of this example of embodiment according to the invention is as follows: If the relay armature 1 is to be moved into the exciting coil, the power of the resetting spring 10 must be over-

come. In addition, the toggle levers 7 must be pressed outwards over the rollers 8 against the action of the regulating spring 13. By the action of the toggle levers 7 upon the relay armature 1 both the start of the relay armature and its stroke will be influenced in the manner intended.

To make this influence clear, in Fig. 2 has been represented the direction of the magnetic force of attraction P_M and the resetting power P_F of the counter-spring in function of the armature stroke s . The direction of the magnetic force of attraction P_M in function of the armature distance s has a hyperbolic character, whereas the resetting power P_F takes a linear course. Both these powers act contrariwise to each other. By turning down the curve for P_F round the x -axis, the magnetic force of attraction and the resetting force of the spring can be better compared with each other. To obtain neat work, the resetting spring must be loaded, so that its characteristic does not begin at zero point. A movement of the relay armature takes place only at the moment, in which $P_M \geq P_F$. The hatched space between the curves P_M and P_F of Fig. 2 corresponds therefore to the entire capacity for work inherent to the armature at the end of the movement in the form of kinetic energy, that is to say, also, to the capacity for work which the relay is able to exert in fulfilling its duty. This capacity for work compared with that of the relays of the first group mentioned hereinbefore is fairly poor. For a sure timed response of the relay it is particularly important that the angle α between the curves for $P_M=f(s)$ and $P_F=f(s)$ for the abscissae $s=0$ shall be as great as possible. According to the invention this is achieved by imparting to the curve $P_F=f(s)$ a sloping instead of a rising course. This modification is attained by the action of the toggle levers 7 upon the relay armature 1, whereby it appears quite easy to obtain a favorable outline of the new curve by suitable disposition of the toggle levers 7 and shaping of the bulge. For the bulge form as per Fig. 3 there is obtained, for instance, a curve $G=f(s)$ according to Fig. 4 for the counter-power. It may be seen therefrom that the curve $G=f(s)$, already represented as turned down in Fig. 4, does not show any continuous outline, but exhibits unsteadiness at the points a , b , c , d . The explanation of the bend is apparent from Fig. 3, in that the generator of the selected bulge form is composed of three single lines, two straight and one curved. Suppose now the rollers 8 be rolling off consecutively on each of these lines, and the power-path-curve thereby each time determined. One obtains for line I a right-slope descent of the counter-power G , as the turning moment of the toggle levers 7 is actually only slightly modified owing to the comparatively small distortion of the lever, whereas, on the other hand, the effective lever arm increases and consequently the counter-power decreases, approximately according to curve I of Fig. 4. When the roller 8 moves over the arc II, it is easy to see that the corresponding curve II has a more pronounced sloping path than curve I, becoming zero for the point with the biggest radius, and negative for the lower portion of the arc, because the counter-power acts now in the same direction as the magnetic force of attraction P_M . For line III the action of the roller likewise assists the magnetic force of attraction, and consequently the corresponding curve III in Fig. 4 runs entirely in the negative region, i. e. so that for increasing s the effective power slightly decreases.

In this way the bends a and b of the curve $G=f(s)$ are readily given. The bends c and d ensue at the moment when the contact between the rollers 8 and the armature 1 suddenly ceases.

5 The power exerted by the rollers upon the armature must then instantaneously become zero.

The opposing force P_A which has to be totally overcome by the magnetic force of attraction P_M is composed, apart from the weight of the armature, 10 of the counter-power P_G exerted by the rollers 8 and the resetting force P_F of the counter-spring 10. In Fig. 5 this resulting opposing force P_A is represented in conjunction with the magnetic force of attraction P_M . The curve 15 $P_A=f(s)$ is thereby displaced upwards for the load of the counter-spring 10. It appears from Fig. 5, that by this new arrangement the sloping path of the P_A -curve, recognised as favorable, is actually attained. In contrast to an ordinary relay, the characteristic of a relay according to 20 the invention reveals the following main advantages:

1. A many times greater angle α , whereby a reliable and distinct response with a definite excitation is ensured.

25 2. Greater capacity for work represented by the larger space enclosed between the curves P_M and P_A .

Further advantages arise out of the easy adjustability of the response limit by setting the 30 pressure of the regulating spring 13 upon the toggle levers 7 and by suppressing much the tendency to buzz. The design of the bulge form of the armature 1 may, of course, differ from that 35 illustrated in Fig. 3 and consequently the characteristic of the relay be adapted to the most exacting requirements. Notably, by suitable selection of the angles on the bulge flank the ratio of the sections A:B in Fig. 5 can be increased or decreased. Furthermore, by modifying the diameter of the rollers 8 and the radius of curvature 40 of the armature bulge, the section C in Fig. 5 can likewise be modified. The value B can for the rest be entirely eliminated, if a shape according to Fig. 6 is imparted to the relay armature 1. In this case the rollers need only be lifted out of the armature groove to then roll off on the curved surface during the whole movement without affecting the armature in the direction of the 45 movement either in the one or in the other sense.

The relay armature, moreover, need not be a rotation-symmetrical body, but may have any other suitable shape. It may be also of tubular 50 form as shown in Figs. 10 and 11 and the lead faces may be fitted as special shoulders. In place of two shoulders only one may be provided at a specially appropriate point. For suppressing eddy currents the last mentioned design may, moreover, be split.

55 The invention is by no means confined to plunger armature relays, but may be applied to rotary and hinged armature relays as well. Fig. 7 reveals such application to a rotary armature relay and Fig. 8 to a hinged armature one.

60 The invention in its broader aspects is not limited to the specific mechanisms shown and described but departures may be made therefrom within the scope of the accompanying claims without departing from the principles of the invention and without sacrificing its chief advantages.

Having now particularly described and ascertained the nature of my said invention and in what manner the same is to be performed, I declare that what I claim is:

1. A relay comprising, in combination, an armature, electromagnetic means for moving said armature from a position of rest to a moved position when energized, latching means engageable with said armature to prevent movement toward moved position, disengageable upon predetermined power applied to said armature to permit said movement, and spring means biasing said armature toward said position of rest whereby said latch means may re-engage said armature upon de-energization of said electromagnetic means.

2. A relay comprising, in combination, an armature having a depression in the surface thereof, electromagnetic means for moving said armature in one direction when energized, spring means opposing such movement of the armature and tending to return the armature on deenergization, and latching means engageable with said armature to prevent movement in said direction, disengageable upon predetermined electromagnetic power applied to said armature to permit said movement, said latching means including a latching member for engagement in said depression and resilient means urging said member toward said armature.

3. A relay comprising, in combination, a cylindrical armature having a circumferential rounded depression in the surface thereof, electromagnetic means for moving said armature in one direction when energized, spring means opposing such movement of the armature and tending to return the armature on deenergization, and latching means engageable with said armature to prevent movement in said direction, disengageable upon predetermined electromagnetic power applied to said armature to permit said movement, said latching means including a pair of pivoted elements carrying rounded contacts for engagement in said depression and spring means engaging said elements biasing said elements toward said armature.

4. A relay comprising, in combination, a cylindrical armature having a circumferential rounded depression in the surface thereof, electromagnetic means for moving said armature in one direction when energized, spring means opposing such movement of the armature and tending to return the armature on deenergization, and latching means engageable with said armature to prevent movement in said direction, dis-

engageable upon predetermined electromagnetic power applied to said armature to permit said movement, said latching means including a pair of pivoted elements carrying rounded contacts for engagement in said depression and spring means engaging said elements biasing said elements toward said armature, and means for varying the tension of said spring means upon said elements.

5. A relay comprising, in combination, a cylindrical armature having a circumferential rounded depression in the surface thereof adjacent one end and a circumferential frusto-conically formed surface between said depression and said adjacent end, electromagnetic means for moving said armature in one direction when energized, spring means opposing such movement of the armature and tending to return the armature on deenergization, and latching means reasably engageable with said armature said means comprising a pair of oppositely disposed pivoted arms having rounded end portions to engage said armature in said depression and on said frusto-conically formed surface and spring means urging said end portions toward said armature.

6. A relay comprising, in combination, an armature having a rounded depression in the surface thereof, electromagnetic means for moving said armature in one direction when energized, spring means opposing such movement of the armature and tending to return the armature on deenergization, and latching means engageable with said armature to prevent movement in said direction, disengageable upon predetermined electromagnetic power applied to said armature to permit said movement said means including a rounded contact member spring pressed into said depression.
